BAND-PASS TRANSFORMER

Joseph B. Gainer, Washington, D. C.

Application August 11, 1945, Serial No. 610,373

10 Claims. (Cl. 178—44)

(Granted under the act of March 3, 1883, as
amended April 30, 1928; 370 O. G. 757)

1

My invention relates to transformers and particularly to transformers utilized in radio-frequency amplifier or oscillator circuits.

In accordance with my invention, the primary and secondary windings of a transformer are mounted in a fixed relative position affording greater than optimum or critical coupling and a tertiary winding inductively related to both the primary and secondary windings is adjustable to reduce their effective mutual inductance to an extent affording the desired frequency-response characteristic, of an interstage transformer for example, or to afford the desired amount of a feedback in an oscillator, detector or amplifier system.

My invention further resides in features of construction and arrangement hereinafter described and claimed.

For an understanding of my invention and illustration of embodiments thereof, reference is made to the accompanying drawings, in which:

Fig. 1, in perspective, shows an interstage transformer.

Fig. 2 is an explanatory figure mentioned in discussion of Figs. 1 and 3.

Fig. 3 schematically shows a portion of an amplifier system using the transformer of Fig. 1.

Fig. 4, in perspective, shows another type transformer.

Fig. 5 schematically shows an oscillator system using the transformer of Fig. 4.

Referring to Fig. 1, the primary winding P and secondary winding S of an interstage transformer T are wound respectively on the tubular forms 1 and 2 suitably fastened to the base member 3. The coil and base assembly is enclosed by a conductive shield 4 provided with lugs, not shown, which pass through notches 5 in the base 3 and through the receiver chassis, or equivalent, not shown. The terminals 6 to 9 fastened to and extending through base 3 provide for external connection of the transformer windings to other circuit elements, for example, Fig. 3, to the output and input electrodes respectively of amplifiers tubes V₁, V₂ for simplicity only shown as triodes. The inductances of the windings P and S may be and usually are more or less exactly equal.

It is usually desired that the frequency-response curve of such an interstage transformer as tuned by condensers C₁, C₂ and/or by the cores 12, 13 shall have the general shape of curve 10, Fig. 2, characterized by a relatively flat top and steep sides to provide for substantially uniform amplification of all frequencies throughout a band of frequencies f₁ to f₂ and with great attenuation for all frequencies lower and higher than f₁ and f₂ respectively.

Because of the interdependent variables involved, it is difficult to design and manufacture radio-frequency transformers which have the

2

desired band-pass characteristics both as to width of band and limiting frequencies: moreover when the desired band-width is but a small fraction of the mean frequency f₀, the required coupling is so small the corresponding relatively great physical separation of the windings enforces, when the usual practice is followed, large overall dimensions of the transformer.

In accordance with my invention however, the 10 windings P and S are purposely positioned close to one another affording a percent coupling which is substantially in excess of optimum or critical and resulting in a band-pass characteristic generally as exemplified by curve 11, Fig. 2. To reduce the mutual inductance of transformer T, there is provided a tertiary winding W comprising one or more turns coupled to and slidably along the primary and secondary windings P and S.

By adjustment of winding W along the coils 20 P and S, the frequency-response characteristic may be varied from one having generally the shape of curve 11 to one having generally the shape of the curve 10. Winding W may be secured in a properly adjusted position by a suitable 25 coil cement, tape or the like. It is understood that the physical position of winding W may be altered to produce either an additive or subtractive effect on the coupling between coils P and S as, by reason of the closeness of coupling between the primary 30 coil P and one part of the winding W and between the secondary coil S and the other part of the winding W, the winding W can be adjusted to have considerable effect on the coupling between coils P and S so that it may be adjusted 35 to the point where it not only reduces the normally over-coupled condition between coils P and S to zero but actually produces a reversal of phase in the output of coil S. The two parts of winding W may be cross-connected, as shown, so 40 that the part on form 2 opposes the secondary coil S or the part of winding W on form 2 may be wound in a direction to aid the secondary coil S when it is desired to increase the mutual coupling between coils P and S. The adjustment 45 of W also can be used to compensate for stray coupling of coil leads or components such as condensers or resistors within the shield 4.

Variation of the mutual inductance of two circuits individually tuned to same frequency, substantially equally and simultaneously shifts the upper and lower resonant frequencies f₃ and f₄ toward or away from the median frequency. Consequently although the aforesaid adjustment of winding W may afford the desired band-pass requirements and shape of curve 10, the position of the frequency band passed may not exactly coincide in the frequency spectrum with the desired band because of manufacturing variations or tolerances in self inductance of windings P 55 and S.

Preferably therefore, the self-inductance of

each of windings P and S may be individually adjusted by cores 12 and 13 which may be of magnetic material, such as powdered iron, or of non-magnetic material such as copper or brass, or in the whole or part of dielectric, the choice of material depending at least in part on the position in the frequency spectrum at which the transformer is to operate. By adjustment of cores 12 and 13, the upper and lower frequencies f_3 and f_4 may be individually shifted so that in combination with winding W, the desired band width and the desired upper and lower frequencies of the band may be accurately determined without need for precise manufacturing tolerances and construction.

As shown in Fig. 1, the cores may be mounted within and rather closely fit the tubes 1 and 2 for adjustment by the rods 14, 15 which are engaged by threaded inserts, 16, 17, Fig. 1 secured to the upper ends of forms 1 and 2. This transformer has the desirable feature that all freely variable tuning adjustments are from the same side of the transformer and usually outside of the chassis, the winding W being fixedly secured in position by cement, tape, or the like when finally adjusted before the shield 4 is placed in position.

Preferably the rods 14, 15 of Fig. 1 and metallic parts electrically connected thereto are grounded through spring material 18 and the shield can 4 to avoid effects of external coupling and capacity during alignment.

In amplifiers used in television receivers for example where the band-width is large, for example 4 to 6 megacycles as contrasted with a maximum of 10 or 15 kilocycles for broadcast reception, damping resistors, such as resistances 19 and 20, may be used.

By way of example, the dimensions of the transformer T for use at frequencies between 50-56 megacycles are as follows:

Overall height	inches	1 $\frac{1}{8}$
Overall diameter	inches	1 $\frac{1}{8}$
Coil forms diameter	inch	$\frac{5}{16}$
Coil forms length	inches	1 $\frac{1}{2}$
Coil form turns (#26 enameled wire)		11
Center to center of coils P-S	inch	$\frac{7}{16}$
Tertiary winding turns		2
Condenser C ₁ , C ₂	mmf	7-10
Resistor pri	ohms	1800
Resistor sec	ohms	2700

From the foregoing dimensions, it is apparent that the coil forms 1 and 2 are spaced from each other about one-eighth of an inch. Thus, as can be seen from Fig. 1, the two parts of winding W have very little mutual inductance therebetween because the turns on form 1 are practically in the same plane as those on form 2 and the crossed connections between them are very short and cross each other substantially at right angles. The latter feature is of considerable importance in eliminating mutual inductance between the parts of coil W as there can be little inductance between very short leads and there is no inductance between leads which cross at right angles in that there can be no interaction between the magnetic fields surrounding such leads.

In absence of an oscilloscope and a sweep-frequency generator suited for wide-band alignment, a signal generator and output meter constitute the only test equipment needed for attainment of proper adjustment of the tertiary winding and cores.

The transformer exemplified in Fig. 4 is for use in an oscillator circuit such for example as shown

in Fig. 5. The construction of transformer T-1, is generally similar to transformer T of Fig. 1 and accordingly need only briefly be described.

The primary and secondary coils P₁ and S₁ are wound respectively on forms 19 and 20 disposed side by side and extending from base 21. Ordinarily the primary turns are fewer in number than the secondary but in any event the mutual coupling of these windings is purposely greater than that required to sustain oscillations.

The mutual coupling may effectively be reduced in control of the feed-back voltage introduced by coil P₁ into the tuned grid circuit C₃, S₁, Fig. 5, by adjustment of the tertiary coil W₁ which for ease of control is wound on tubular forms 26, 27 slidably respectively along forms 19, 20 and connected by the insulating bridging member 28. The knob 29 and rod 30 connected to member 28 permit adjustment externally of the transformer shield can 31 of the position of the feed-back control link W₁. Again the phase of the tertiary winding may be to aid or oppose the mutual coupling.

A similar transformer may be used in a regenerative or degenerative amplifier or detector stage in which the feed-back voltage may be determined or adjusted by a tertiary winding W₁. Such transformer may for example be used to advantage in a regenerative detector circuit utilizing a screen grid tube, Fig. 5. Ordinarily in such circuit, feed-back is controlled by varying the screen grid voltage to maintain the operating point (i. e. below the threshold of oscillation). The chief difficulty or objection is that the voltage supplied to the screen may not correspond with the operating point of the tubes characteristic curve affording the desired or maximum sensitivity. With the present arrangement the screen voltage may be set independently at a point for maximum sensitivity and the feed-back independently controlled by adjustment of link W₁. In addition, this construction in common with that of the interstage transformer allows for a reduction on the physical size of the unit and elimination of need for close tolerances in manufacture.

Typical values for an oscillator or a regenerative detector embodied in Fig. 5 operating between 30-50 megacycles with tetrode V₁ follow:

P ₁	6 turns (#22 wire)
S ₁	15 turns (#22 wire)
Forms diameter	$\frac{5}{16}$ "
Spacing between coil centers	$\frac{7}{16}$ "
W ₁	2 turns (#22 wire on $\frac{1}{2}$ " forms)
C ₁	250 micro-microfarads (fixed)
C ₂	50 micro-microfarads (variable)
R ₁	33,000 ohms (grid resistor)
C ₃	1 micro-farad (fixed)
L ₁	High impedance choke 50 henries

This is an electron coupled feed-back circuit and it is understood that the same application can be used in other types, i. e. Armstrong regenerative type oscillator, tuned grid-tuned plate.

The transformer shown in Fig. 4 may also be utilized to coupling the input circuit of an amplifier, detector or oscillator tube to an antenna circuit or transmission line for reception or transmission of radio-frequency energy. The adjustment of winding W permits impedance matching or desired degree of coupling even though for

compactness the primary and secondary windings are themselves overcoupled.

The invention described herein may be manufactured and used by or for the Government of the United States of America for governmental purposes without the payment of any royalties thereon or therefor.

What I claim is:

1. A structure comprising a radio frequency transformer including primary and secondary windings inductively coupled and disposed in close side by side relation with their axes substantially parallel, a two-loop closed circuit tertiary winding slidably mounted on said structure having at least one turn in each of its loops and one of its loops substantially coaxial with said primary winding and the other of its loops substantially coaxial with said secondary winding, said tertiary winding being adjustable as a unit towards and away from adjacent ends of said primary and secondary windings to effect thereby a variation in the mutual coupling between the primary and secondary windings.

2. The radio frequency transformer of claim 1 in which the tertiary winding is arranged to produce a flux in opposition to the flux linkage between said primary and secondary windings.

3. The radio frequency transformer of claim 1 in which the tertiary winding is arranged to produce a flux aiding the flux linkage between said primary and secondary windings.

4. The radio frequency transformer of claim 1 including means for determining the location in the frequency spectrum of the band of frequencies passed by said transformer comprising cores adjustable to vary the self-inductance of said primary and secondary windings.

5. A structure comprising a radio frequency transformer including primary and secondary windings inductively coupled and disposed in close side by side relation with their axes substantially parallel, means for determining the location of the frequency band passed by said transformer comprising means to adjust the self inductance of at least one of said windings, a two-loop closed circuit tertiary winding slidably mounted on said structure having at least one turn in each of its loops and one of its loops substantially coaxial with said primary winding and the other of its loops substantially coaxial with said secondary winding, said tertiary winding being adjustable as a unit towards and away from adjacent ends of said primary and secondary windings to effect thereby a variation in the mutual coupling between the primary and secondary windings.

55

6. The radio frequency transformer of claim 5 in which the tertiary winding is arranged to produce a flux in opposition to the flux linkage between said primary and secondary windings.

5 7. A radio frequency transformer comprising first and second winding forms disposed in close side by side relation with their axes substantially parallel, a primary winding disposed on said first form, a secondary winding disposed on said second form substantially in juxtaposition to said first winding and inductively coupled thereto, a two-loop closed circuit tertiary winding having at least one turn in each of its loops and one of its loops disposed on said first form substantially coaxial with said primary winding and the other of its loops disposed on said second form substantially coaxial with said secondary winding, said tertiary winding being adjustable as a unit along said forms towards and away from adjacent ends of said primary and secondary windings to effect thereby a variation in the mutual coupling between the primary and secondary windings.

10 8. The radio frequency transformer of claim 7 in which the tertiary winding is arranged to produce a flux in opposition to the flux linkage between said primary and secondary windings.

15 9. The radio frequency transformer of claim 7 including means for determining the location in the frequency spectrum of the band of frequencies passed by said transformer comprising cores adjustable within said winding forms to vary the self-inductance of said primary and secondary windings.

20 10. The radio frequency transformer of claim 9 in which the tertiary winding is arranged to produce a flux in opposition to the flux linkage between said primary and secondary windings.

JOS. B. GAINER.
